UNITED STATES PATENT OFFICE.

GEORGE JAMES PEACOCK, OF BUFFALO, NEW YORK.

COMPOSITION HORSESHOE.

SPECIFICATION forming part of Letters Patent No. 717,614, dated January 6, 1903.

Application filed July 19, 1900. Serial No. 24,157. (No model.)

To all whom it may concern:

Be it known that I, GEORGE JAMES PEACOCK, of Buffalo, county of Erie, and State of New York, have invented a new and useful 5 Improvement in Composition Horseshoes, of which the following is a full, clear, and exact description, reference being had to the accompanying drawings, forming part of this specification, in which—

10 Figure 1 is a bottom plan view of my improved shoe. Fig. 2 is a side elevation, partly broken away; and Fig. 3 is a top plan view.

15 My invention relates to that class of horse-shoes which are formed, at least in part, of a composition, such as a combination of rubber or analogous material, with a fabric, and is designed to strengthen and improve such shoes by providing an improved metal toe- 20 piece, which is secured in the composition by providing a bar connecting the heel portions of the shoe and by using a separate toe-clip, which is secured to the shoe after it is formed.

25 In the drawings, 2 represents the toe portion and 3 the heel portions of the composition shoe, which is preferably formed in accordance with my copending application, Serial No. 4,345, filed February 7, 1900, for composition horseshoes, layers of heavy duck or 30 other fabric being used, with layers of ground canvas and rubber between each ply. The shoe is shown with a top layer of canvas 4, which is next to the hoof, and with a central layer 5 in the intermediate part of the shoe, 35 the remainder of the shoe being formed of composition, such as above described.

In forming the shoe into shape by heavy 40 pressure I mold into the shoe a toe-iron 6, which is provided with one or more inwardly-projecting lugs 7, which are of dovetail shape and hold the toe-iron firmly in place. This iron may be made of different lengths, and its legs may be much shorter than those shown. 45 These legs 8 are provided with nail-holes 13, which extend through the recessed sides of the shoe, and as the toe-iron is made of malleable metal where the longer legs are used the shoe may be bent to fit the hoof and will remain in the shape to which it is bent. The 50 toe-iron is of considerably less thickness than

that of the shoe, so that there is a layer of the composition forming a cushion for the hoof.

After the shoe has been formed and pressed to shape with the toe-iron pressed into it and 55 then vulcanized the toe-clip 9 is secured to the shoe by driving the inwardly-projecting tongues or pins 10 into the inner part of the toe portion. This part of the shoe is preferably molded with a recess, of the same 60 thickness as the clip, so that the clip when in place will be flush with the top face of the shoe, and the clip may be further secured by a nail or screw driven through a hole 11 in its body. 65

For certain purposes, especially for a winter shoe, I preferably provide the molded cross-bar 12, which connects the heel portions and is flush with the bottom face of the shoe, being thinner than the shoe-body and preferably of about one-half its thickness, as indicated in dotted lines in Fig. 2. This bar will prevent slipping on wet or icy pavements and allows expansion and contraction of the hoof, while preventing it from spreading. 75 The bar being lowered below the top face of the shoe gives the desired frog-pressure without exerting too strong a force.

The shoe is provided with molded recesses 13', which extend upwardly for a portion of 80 its thickness and register with the holes in the toe-iron throughout the length of this iron. These molded recesses direct the nails and make easy the application of the shoe to the hoof. 85

The advantages of my improved shoe will be apparent to those skilled in the art, since the shoe does not give the extreme frog-pressure of an iron shoe, can be bent to fit the hoof, and will remain in place after being fitted. 90 The keys or lugs 7 of the toe-iron hold it firmly in place, and the hoof is cushioned above this iron. The clip is simple and may be easily attached and holds the shoe in place, preventing it from being forced back on the 95 hoof. The bar at the heel serves to prevent slipping, and where this is used the shoe can be shortened or narrowed at the heel by rasping, there being no metal in the rear of the nails. 100

Many variations may be made in the composition used, the form and size of the toe-iron and the clip, and the shoe may be made with or without the cross-bar without departing from my invention.

I claim—

1. A composition horseshoe having a metal toe-iron molded therein and secured by inwardly-projecting lugs having enlarged ends 10 embedded in the composition; substantially as described.

2. A composition shoe having a removable toe-clip secured thereto by prongs driven into the material of the shoe; substantially as described.

3. A removable toe-clip for composition horseshoes having prongs arranged to be

driven into the material of the shoe; substantially as described.

4. A composition horseshoe having a metal 20 toe-iron secured thereto by lugs which project inwardly beyond the iron, and are embedded in the composition of the shoe, said toe-iron having outer recessed portions with exposed nail-holes leading into the composition portion of the shoe; substantially as described.

In testimony whereof I have hereunto set my hand.

GEORGE JAMES PEACOCK.
